UNITED STATES PATENT OFFICE.

CHARLES D. WIEMER, OF LOS ANGELES, CALIFORNIA.

DESIGN FOR A DIRECTION SIGNAL.

Application filed June 19, 1922. Serial No. 2,731. Term of patent 7 years.

To all whom it may concern:

Be it known that I, CHARLES D. WIEMER, a citizen of the United States, residing at 3036 South Main Street, in the city and county of Los Angeles and State of California, have invented a new, original, and ornamental Design for Direction Signals, of which the following is a specification, reference being had to the accompanying drawing, forming part thereof.

Figure 1 of the drawing is an elevation of a direction signal, showing my new design. Figure 2 is a plan view of the same.

I claim:

The ornamental design for a direction signal, as shown.

CHARLES D. WIEMER.
